[57] CLAIM

The ornamental design for a tire, as shown and de-
scribed.

DESCRIPTION

FIG. 1 is a perspective view of a tire showing my new
design, it being understood that the tread pattern is
repeated throughout the circumference of the tire, as
shown schematically by solid lines, the opposite side
being substantially the same as that illustrated; and
FIG. 2 is a perspective view of a tire showing a second
embodiment of my new design, it being understood that
the tread pattern is repeated throughout the circumfer-
ence of the tire, as shown schematically by solid lines,
the opposite side being substantially the same as that
illustrated; and

FIG. 3 is an enlarged plan view of the tread pattern of
the tire of FIG. 2.
